UNITED STATES PATENT OFFICE

96,057

DESIGN FOR A SHOE

Jack Scacco, New York, N. Y.

Application January 21, 1935, Serial No. 54,969

Term of patent 3½ years

To all whom it may concern:

Be it known that I, Jack Scacco, a citizen of the United States and resident of New York city, in the county of New York and State of New York, have invented a new, original, and ornamental Design for a Shoe, of which the following is a specification, reference being had to the accompanying drawing, forming part thereof, in which,

Fig. 1 is a plan view of the shoe showing my new design; and

Fig. 2 is a side perspective view of the shoe shown in Fig. 1.

A dominant feature of the design resides in the

plain single piece elongated vamp forming a T strap which is attached by a button on each side to the upper and thus providing substantial semi-circular openings on either side of the shank of the shoe, with openings thus formed spacing the vamp and upper along the sides of the shoe shank. A further feature resides in the borders of these openings being ornamented by narrow bands of trimming of contrasting material.

I claim:

The ornamental design for a shoe as shown and described.

JACK SCACCO.
